UNITED STATES PATENT OFFICE

2,366,088

PIPE HEATING FURNACE

John L. Coody, Tulsa, Okla.

Application April 27, 1944, Serial No. 532,989

7 Claims. (Cl. 263—2)

The invention relates to pipe heating furnaces, particularly adapted for heating pipe sections of large diameter, preparatory to placing the pipe sections on a bending table for bending the pipe sections around a form.

A further object is to provide a pipe section heating furnace, through which furnace a plurality of pipe sections are progressively moved to a discharge point where the pipe sections are removed as needed for the bending operation.

A further object is to provide trackways at opposite sides of the furnace and extending entirely across the furnace and shoes in said trackway for supporting the pipe ends in spaced relation so that the products of combustion within the furnace will pass entirely around the portions of the pipe sections within the furnace. Also to incline the trackways so that the pipe sections will move by gravity towards the discharge side of the furnace.

A further object is to provide the discharge side of the furnace between the trackways with filler members so that the lower pipe section will act as a seal against escape of gases from the furnace.

A further object is to provide the lower portion of the furnace with a transverse supporting member engaging the lower sides of the pipe sections between the trackways for preventing sagging of the pipe sections, incident to the heating thereof.

A further object is to provide a pipe section heating furnace through which pipe sections, to be heated, will move by gravity from a pipe feeding position to a pipe discharge position on the opposite side of the furnace.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a perspective view of the furnace, showing pipe sections in position therein.

Figure 2 is a vertical transverse sectional view through the furnace.

Figure 3 is a detail perspective view of portions of one of the trackways, showing the pipe receiving shoes, and pipe ends supported therein.

Referring to the drawings the numeral 1 designates the lower portion of the furnace having a combustion chamber 2 therein. Fuel is fed to

the combustion chamber 2 through a burner 3, and the products of combustion pass upwardly into the chamber 4 of the dome section 5 of the furnace, and then outwardly through the flue 6 to the atmosphere.

The dome section 5 is rigidly supported, upwardly spaced, from the lower section 1 by the rigid arms 7 carried by the stationary uprights 8 and by the downwardly extending arms 9, the lower ends of the arms 9 being connected to the oblong shaped frame 10, formed from angle iron, therefore it will be seen that the dome is rigidly supported at all times.

The end bars 11 of the frame 10 are formed from channel iron to form guides in which the refractory pipe holding spacer members 12 are guided; there being similarly shaped channeled members 13 carried by the ends of the furnace section 1 for guiding the lower spacer blocks 12.

10 The bars 13 extend beyond the rear side of the furnace, clearly shown in Figure 2, so that pipe sections 14 can be assembled in the spacer blocks to the rear of the furnace, and as the guide channels 11 and 13 incline downwardly and forwardly

15 it will be seen that the pipe sections will be progressively fed downwardly and forwardly through the combustion chamber 2 to the forward side of the furnace by gravity. The lower forward ends of the guide channels 13 terminate in upwardly extending stop arms 15 and by referring to Figure 2, it will be seen that when the pipe section 14, shown in dotted lines, has been heated

20 the upper spacer block 12 can be removed, then the pipe section removed for a bending operation on a bending table; after which the lower block 12 is removed and then all of the

25 block sections, with the pipe sections therein, will feed downwardly by gravity so that the next pipe section, which has been previously heated, is in position to be removed for bending purposes.

30 It will be noted that the lower section of pipe will cool some on its outer side and this cool side is placed against the form around which the section is bent, hence will be free of wrinkles incident to the bending operation while the hot outer side will be ductile and will easily stretch

35 and will be free of wrinkles. The type of bending machine is disclosed in my co-pending application, Serial Number 532,988, filed April 27, 1944.

40 It will be noted that the lower pipe section 14 substantially closes the space between the dome and the base at the point of discharge, thereby preventing excessive loss of heat during the heating operation.

45 It has been found desirable to support the

50

55

55 It has been found desirable to support the

pipe sections 14 within the furnace intermediate their ends to prevent sagging of the sections and to accomplish this result a water cooled upwardly inclined supporting member 16 is provided. Member 16 engages the under sides of the pipe sections 14, consequently the pipe sections are maintained straight at all times. A circulation of water may be maintained through the support 16 by means of a water supply pipe 17, and a discharge pipe 18. It will be noted that the ends of the pipe sections 14 extend beyond the ends of the furnace, and the heating is centrally of the sections where the bend is to take place. The furnace is particularly adapted for bending pipe of large diameter, as high as 24 inches, which is quite common around refineries.

The spacer members 12 are provided with arcuate recesses 19 conforming to the cross sectional shape of the pipe, however they are preferably spaced as at 20 to take care of expansion and contraction.

From the above it will be seen that a pipe heating furnace is provided which is simple in construction and one through which pipe sections are progressively fed by gravity to the point of discharge.

The invention having been set forth what is claimed as new and useful is:

1. A furnace for heating pipe sections, said furnace comprising a lower base section having a combustion chamber therein, a dome section above the base section in spaced relation thereto, transversely extending downwardly and forwardly inclined spacer block trackways carried by the base section and the dome section, separable spacer blocks mounted in said trackway for the reception of opposite ends of pipe sections, said pipe sections and spacer blocks moving by gravity through the combustion cham-

ber from the rear side of the furnace to the forward discharge side as the pipe sections and spacer blocks at the discharge side are removed from the trackways.

5. 2. A device as set forth in claim 1 including a pipe section sag brace extending through the furnace in engagement with the under sides of the pipe sections.

10. 3. A device as set forth in claim 1 including a brace extending through the combustion chamber in engagement with the under side of the pipe sections, and means for cooling said sag brace.

15. 4. A device as set forth in claim 1 wherein the lower spacer block guides extend beyond the rear side of the furnace, thereby allowing the assembling of spacer blocks and pipe sections to the rear of the furnace to be fed through the furnace as pipe sections are removed from the discharge side of the furnace.

20. 5. A device as set forth in claim 1 including stop members in the path of the spacer blocks at the discharge side of the furnace for limiting the lower pipe section to the discharge point outside the furnace.

25. 6. A device as set forth in claim 1 wherein the spacer blocks are formed from refractory material and are provided with registering recesses for engaging opposite sides of the pipe section 30 ends, and substantially closing the space between the base section and the dome section of the furnace at its ends.

35. 7. A device as set forth in claim 1 wherein the spacer blocks and pipe sections are so positioned and proportioned whereby the pipe sections will substantially form closures for the space between the furnace section at the rear and forward sides of the furnace thereby preventing excessive loss of products of combustion.

JOHN L. COODY.
